UNITED STATES PATENT OFFICE

171,761

DESK SET

Walter H. Henning and Eugenia Williams
Henning, Los Angeles, Calif.

Application October 12, 1953, Serial No. 27,138

Term of patent 14 years

(Cl. D74—1)

To all whom it may concern:

Be it known that we, Walter H. Henning and Eugenia Williams Henning, both citizens of the United States, residing at Los Angeles, in the county of Los Angeles and State of California, respectively, have invented a new, original, and ornamental Design for a Desk Set, of which the following is a specification, reference being had to the accompanying drawing forming part thereof.

Fig. 1 is a perspective view of a desk set embodying our new design;

Fig. 2 is a rear view in elevation of the same; and

Fig. 3 is an end view in elevation of the same.

We claim:

The ornamental design for a desk set, as shown.
WALTER H. HENNING.
EUGENIA WILLIAMS HENNING.
